UNITED STATES PATENT OFFICE.

ALBERT B. DICK, OF CHICAGO, ILLINOIS, ASSIGNOR TO THE A. B. DICK COMPANY, OF SAME PLACE.

TYPE-WRITING MACHINE.

SPECIFICATION forming part of Letters Patent No. 545,403, dated August 27, 1895.

Application filed August 30, 1893. Serial No. 484,355. (No model.)

To all whom it may concern:

Be it known that I, ALBERT B. DICK, a citizen of the United States, residing at Chicago, in the county of Cook and State of Illinois, 5 have invented a certain new and useful Improvement in Type-Writing Machines, of which the following is a specification.

The object of my invention is to secure a type-writing machine of low cost which shall 10 be capable of doing work as good, or nearly so, as any of the type-writing machines now on the market, and which shall be capable of manifolding and be especially adaptable for operation in connection with the production 15 of stencils by the well-known mimeograph process of producing type-writer stencils.

My invention consists in the devices and combinations of devices, hereinafter described and claimed.

20 In the accompanying drawings, forming a part of this specification, Figure 1 is a front elevation with certain of the parts broken away to better reveal details. Fig. 2 is a plan view thereof with the platen and connected mechanism removed. Fig. 3 is a plan view of the frame of the machine. Fig. 4 is a side elevation thereof, partly in section. Fig. 5 is a plan view of the platen-holding frame. Fig. 6 is a sectional elevation through the type- 25 wheel with some of the operating parts therefor. Fig. 7 is a detail of the paper-shelf and platen. Fig. 8 is a plan view of the type-wheel, gear, and sector. Fig. 9 is a detail of the lever movement for operating the feed- 30 pawl, alignment-tooth, and hammer. Fig. 10 is a detail side view of the carriage-feed pawl and rack.

The frame of the machine is secured on any suitable table A, and comprises a base B; 35 from which rise at the rear end thereof a vertical plate C, and from near the front thereof, at the sides, two posts D. The rear plate C is cast with split sleeves E for receiving the rack-rod of the carriage-feed, and has projecting from it toward the front of the machine two extensions F G, in the upper of which extensions at f is stepped the spindle for the type-wheel, and between which extensions, at points f' g, passes the spindle 45 carrying the mechanism for rotating the type-

wheel. Two lugs H also extend from the back plate of the machine, and these lugs serve to receive the pivot for the lever movement operating the feed. A post H' for the bell also projects from said back plate. At each side 55 of the plate F extend two shoulders I I, which receive a plate in which the upper end of the type-spindle has its bearing and on which also swings the bell-hammer. The posts D D are connected by a plate J, which plate has 60 upward projections K K for receiving the rock-shaft, hereinafter to be described, and outward and downward projections L L, which receives another rock-shaft for operating the hammer. Still other upward projections M M 65 receive the front scale, and another downward and outward projection N receives the movable piece, which is struck by the hammer and operates the type; also, rising from the front plate are two short posts O O, connected by a raised rib P. Upon said short posts is supported the operating-board of the machine with an index-lever having a bearing upon the said rib P.

It is to be understood that the parts of the 70 frame just described can be of cast metal, and that by this construction simplicity and economy in manufacture are attained.

The operative parts of the machine may be best described by describing separately the 75 type-wheel, the feed mechanism, the operating-board and index, and the printing mechanism.

The type-wheel is preferably constructed of two separate plates of metal 1 2, the upper 80 and lower plates both being provided with a series of teeth 3, forming slots for the reception of the loose type 4, which type are shouldered, as shown, so as to prevent dropping through the said slots, and provided with a 85 stem or spindle X, which projects below the lower edge of the lower plate 2. Said plates are connected together by a band 5, of metal or other suitable material, which passes into a groove on the lower side of the upper plate 90 1 and a corresponding groove on the upper side of the lower plate 2. By this construction it will be seen that the type-wheel is 95 adapted to receive any kind of type, and that the type can be readily inserted in place and 100

as readily removed, either for the purpose of changing the font or to replace worn-out characters.

The operating-board and index comprise a slotted sector-shaped piece 6 and an operating-lever 7. Said slotted sector is supported from the frame of the machine, and has arranged on it in any desired order the letters and characters corresponding to the type on the type-wheel and arranged in the same order. The index-lever at its rear end is rigidly secured to the spindle of the toothed sector 8, which of course turns with the movement of the lever and operates the gear 9 on the spindle of the type-wheel, whereby movement is communicated to the type-wheel in any desired direction. Of course it will be understood that the number of teeth on the gear and sector, respectively, are so calculated with respect to the number of type on the type-wheel that for a given movement of the index-lever a number of characters on the type-wheel will move past the printing-point in correspondence with the number of characters on the operating-board, past which the index-lever has moved. The index-lever passes underneath the operating-board 6 and has three projections 10, 11, and 12, the central one of which 11 enters into the arc-shaped slot in the operating-board and the other two of which are adjacent to the outer edges of the said board, as shown. These projections are provided with index-lines and with a term designating the character of printing effected by their operation—as, for instance, the middle projection may contain the word "Caps," while the other two projections contain, respectively, "Figures, Characters," and "Small." This index-lever is preferably provided with a pivoted handle 13, which permits the free and easy operation of said index-lever.

The platen 14 is carried in the frame 15, which is preferably of cast metal, which frame is carried by the rack-rod 16, which in turn is supported in the split sleeves E E. The platen may be of the usual construction found in standard machines, such as the Remington and Caligraph, and is provided at one end with a ratchet-wheel 17, controlled by a pawl 18, pivoted in said frame 15. A milled wheel 19 is also provided to facilitate the turning of the platen by hand for line-spacing. The paper-shelf 20 of the carriage 55 is of the usual construction and extends for nearly the full length of the platen and is pivoted at each end in the side of the frame 15, as shown at 21, Figs. 5 and 7. At each end of the spindle 21 a spring 22, one end of which is coiled around the spindle 21 and the other end of which is fastened to the side of the paper-shelf, exerts pressure on the lower end of the paper-shelf, so as to throw that end against the platen. A roller 22^a is carried at 60 this end by the paper-shelf, and hence an even pressure is exerted upon the paper in the machine, and the same is kept from slipping, while at the same time it may be easily removed by pressing the upper end of the paper-shelf toward the platen.

The cylinder-scale 23 is held in position by the metal strips 24 25, the front end of which is secured to the front of the frame 15, as shown in Fig. 1, and the rear end of which rests, as shown in Figs. 5 and 7, on the spindle 21 of the paper-shelf. The envelope-holder is formed from a strip 26, bent partially around the cylinder, the front end of which is secured to the frame 15, and which is tapered to a point and runs along on the upper edge of the front scale 30.

27 is an indicator, which projects downwardly over the front scale 30.

28 29 are sheaves journaled to the frame 15 and supporting the front of the carriage upon the upper edge of said scale.

The feed mechanism is operated from the plate 31, pivoted on the base B at one side of the machine. This pivoted plate is connected by a series of straight and elbow levers 32, 33, 34, 35, 36, and 37 to the feed-dog 38, said feed-dog engaging with the teeth on the rack 16. It will be obvious that by a downward movement of the plate 31 the system of levers connected therewith will be so operated as to withdraw the dog from one tooth and insert it in the next, and through the action of the spring 39, one end of which is connected with the elbow-lever 35 and the other end with the frame of the machine, the rack and connected mechanism will be fed forward one tooth, the dog being held up to the rack by the spring 38.

The printing movement is effected through a plate 40, which is pivoted at 41 on the post D at the same side of the machine as is pivoted the feed-operating plate. Attached to the rear end of the said platform is a lever 42, which is connected with the crank 43 of a rock-shaft 44, which rock-shaft at one end carries the hammer 45.

It will be obvious that by pressing the plate 40 the crank-arm 44 will be moved and the hammer 45, which is rigidly connected therewith, will swing. In the path of the hammer is a movable anvil 46, in the form of a plate of metal, with two pins or extensions 47 47, which prevent it from dropping through the slot in the projecting end of the main frame. The movable anvil is directly beneath the printing position of the type, and is in line therewith, so that when it is struck by the swinging hammer it will be projected upward against the bottom surface of the type, and hence will force the type from their pockets or sockets against the paper, and thus effect the printing.

By causing the hammer to contact with the anvil instead of directly with the ends of the type I am able to use a hammer of any suitable shape. The anvil is of such width that it will contact with but one of the type at a time, whereas if the hammer struck directly against the type more than one of them might be impelled upwardly against the platen.

The alignment of the machine is secured by providing a finger 48 on a rock-shaft 49, which is shown as secured to said rock-shaft by a sleeve and set-screw 50. Said rock-shaft is operated from the platform 40 through lever 42 and link 51, which connects the rocker-arm 52 with the rocker-arm 44, whereby, by the movement of the platform 40 for the purpose of effecting the printing, 5 the finger 48 will be moved into the teeth of the lower plate 2 of the type-wheel, and as the spaces between these teeth correspond to the type it is obvious that the wheel will be locked in the printing position during the 10 moment of printing and that the finger entering from beneath can enter between said teeth and thus effect true registration.

The ink-ribbon 59 is wound upon two spools 54, 55—one on each post D—of the machine. The spool 55 is provided with a winding-arm 56, and the other spool 54 is provided with ratchet-teeth 57, with which engages a pivoted pawl 58, resting upon a spring 58^a, (shown partly in dotted lines in Fig. 2, said 20 spring being for the main part beneath the platform 40,) whereby each movement of the platform to effect a printing operation effects a partial rotation of the spool, and hence a feed of the ribbon. A dog 60 prevents a 25 backward movement of the spool, while two guide-plates 61, 61, supported on the posts K, K, one being located on each side of the type-wheel, guide and steady the ribbon. As shown, a projection 60^a from the dog 60 rests 30 upon the pawl 58, said pawl being provided with a finger-piece 58^b, whereby when the pawl is moved out of engagement with the ratchet-teeth the dog will be simultaneously moved out of engagement, thus by one movement 35 freeing the spool, so that winding may begin. By providing a lip 62 on the plate 31, which lip enters beneath the bottom of the plate 40, I am enabled by the downward movement of said plate 40 to also move the 40 plate 31, and hence during the printing operation I am enabled also by the same stroke to effect the carriage-feed, although I may, when desired, feed the carriage separately simply by operating 31 alone.

50 The bell 63 is suitably supported from a post cast on the back plate of the frame, and its hammer 64 is suspended from a plate 65, in which is supported the upper end of the spindle of the type-wheel. The bell-ringer 66 is adjustably secured on the rack-rod 16 by a set-screw 67. From the plate 65 extends a light spring 68, which bears on two or three of the type at the printing-point, so as to return them and prevent them from jumping 55 out at other points, the balance of the shield-plate 65, which extends over the rear extension of the type, preventing the same from being jarred out of the slots.

The operation of the machine will readily 60 be understood from the foregoing description, it being necessary only to remark that the loose type are projected upward against a

platens above the same, whereby an action analogous to the action of a standard machine, such as the Remington, is obtained—that is 70 to say, by this arrangement a swinging platen may be used which can be handled in the same manner as is the platen on any ordinary machine. It will also be understood that I am not limited to the precise details of the 75 mechanism for operating the parts shown by me, and especially may the anvil be dispensed with, the hammer being so arranged as to strike the type or a projection therefrom directly.

I claim—

1. In a type-writing machine, the combination of a type-wheel revoluble in a horizontal plane, a movable index beneath the type-wheel and connected therewith for revolving 85 the same, a plurality of type-bearing plates or spindles loosely carried by said type-wheel and arranged radially in a single row and capable of reciprocating vertically a printing character at the upper end of each of said 90 plates or spindles, an alignment finger adapted to engage with and lock said type-wheel, and a hammer adapted to elevate one of said type-bearing plates or spindles when the type-wheel is locked, substantially as described. 95

2. In a type writing machine, the combination of a vertical shaft, a type-wheel carried thereby and comprising a lower plate and an upper plate connected together and revolving in a horizontal plane, a movable index beneath said type-wheel and connected therewith for revolving the same, a plurality of type-bearing plates or spindles vertically mounted in said lower and upper plates, a printing character carried by the upper end 100 of each of said type-bearing plates or spindles, a plurality of teeth extending entirely around the periphery of the lower plate, an alignment finger adapted to engage between said teeth and to lock the type-wheel, and a hammer 105 adapted to elevate one of said type-bearing plates or spindles when the wheel is locked, substantially as described.

3. In a typewriting machine, the combination of a type-wheel revoluble in a horizontal 115 plane, mechanism beneath the type-wheel for revolving the same, a plurality of type-bearing plates or spindles carried by said type-wheel and capable of reciprocating vertically, a printing character carried by the upper end 120 of each of said plates, an alignment finger adapted to engage with and lock said type-wheel, a hammer adapted to elevate one of said type bearing plates or spindles when the wheel is locked and mechanism connected 125 with said alignment finger and said hammer for operating the same simultaneously, substantially as described.

4. In a typewriting machine, the combination of a type-wheel revoluble in a horizontal 130 plane, mechanism beneath the type-wheel for revolving the same, a plurality of type-bearing plates or spindles carried by said type-wheel and capable of reciprocating vertically,

10 a printing character carried by the upper end of each of said plates or spindles, an alignment finger adapted to engage with and lock said type-wheel, a hammer adapted to elevate one of said type-bearing plates or spindles when the wheel is locked, a finger plate pivoted to the frame of the machine, and connections between said finger plate and said alignment finger and said hammer, whereby said alignment finger and said hammer will be operated simultaneously, substantially as described.

15 5. In a typewriting machine, the combination of a type-wheel revoluble in a horizontal plane, mechanism beneath the type-wheel for revolving the same, a plurality of type-bearing plates or spindles carried by said type-wheel and capable of reciprocating vertically, a printing character carried by the upper end of each of said plates or spindles, an alignment finger adapted to engage with and lock 20 said type-wheel, an anvil mounted beneath said type-wheel near the periphery thereof and adapted to be elevated and engage with one of said type-bearing plates or spindles when the type-wheel is locked, and a hammer adapted to engage with and elevate the anvil, substantially as described.

30 6. In a typewriting machine, the combination of a type-wheel revoluble in a horizontal plane, mechanism beneath said type-wheel for revolving the same, a plurality of type-bearing plates or spindles carried by said type-wheel and capable of reciprocating vertically, a printing character carried by the upper end of each of said type-bearing plates or spindles, an alignment finger adapted to engage with and lock said type-wheel, an anvil mounted beneath the periphery of said 35 40 type wheel and adapted to be elevated and engage with one of said type-bearing plates or spindles, a hammer adapted to engage with and elevate the anvil, a finger plate pivoted to the frame of the machine, and connections between said finger plate and said alignment finger and said hammer for simultaneously operating said alignment finger and said hammer, substantially as described.

45 7. In a typewriting machine, the combination with a type-wheel carrying its type loosely in a horizontal plane, of a movable index by the movement of which said type-wheel is rotated in said horizontal plane, and a movable hammer, and an alignment finger operating independently of the index movement whereby the type-bearing wheel is first brought into position and the printing character operated, substantially as described.

55 8. In a type-writing machine, the combination of a type-wheel revoluble in a horizontal plane, mechanism beneath the type-wheel for revolving the same, a plurality of type-bearing plates or spindles carried by said type-wheel and capable of reciprocating vertically, 60 65 a printing character carried by the upper end of each of said plates or spindles, an alignment finger adapted to engage with and lock

90 said type-wheel, a hammer adapted to elevate one of said type-bearing plates or spindles when the type-wheel is locked, a rack bar carried by the frame of the machine, a finger plate pivoted to the frame of the machine, mechanism connected with said finger plate for feeding said rack bar, and a platen mounted upon said rack bar and carried by the 95 same, substantially as described.

9. In a typewriting machine, the combination of a type-wheel revoluble in a horizontal plane, mechanism beneath the type-wheel for revolving the same, a plurality of type-bearing plates or spindles carried by said type-wheel and capable of reciprocating vertically, a printing character carried by the upper end of each of said plates or spindles, an alignment finger adapted to engage with and lock 80 said type-wheel, a hammer adapted to elevate one of said type-bearing plates or spindles when the wheel is locked, a rack bar carrying a platen mounted in the frame of the machine, a pawl or dog engaging with said rack bar, a finger plate pivoted to the frame of the machine and connections between said finger plate and said pawl or dog for feeding the rack bar intermittently, substantially as described.

95 10. In a typewriting machine, the combination of a type-wheel revoluble in a horizontal plane, mechanism beneath the type-wheel for revolving the same, a plurality of type-bearing plates or spindles carried by said type-wheel and capable of reciprocating vertically, a printing character carried by the upper end of each of said plates or spindles, an alignment finger adapted to engage with and lock said type-wheel, a hammer adapted to elevate one 100 105 of said type-bearing plates or spindles when the type-wheel is locked, a rack bar carrying a platen mounted in the frame of the machine, a pawl or dog engaging with said rack bar, a finger plate 31, pivoted to the frame of the 110 machine, connections between said finger plate 31 and said pawl or dog for retracting the same, a spring connected with said pawl or dog for advancing the same and feeding the rack bar intermittently, a finger plate 40, 115 pivoted to the frame of the machine and overlapping the finger-plate 31, and connections between said finger plate 40 and said alignment finger and hammer for simultaneously operating said alignment finger and said hammer, substantially as described.

11. In a typewriting machine, the combination of a ribbon carrying spool provided with ratchet teeth, a feed pawl and detaining dog, said dog being provided with a finger overlapping said pawl, whereby, by the movement of the pawl, the dog is moved out of engagement with the ratchet teeth, substantially as described.

12. In a typewriting machine, the combination of a type-wheel revoluble in a horizontal plane, mechanism beneath the type-wheel for revolving the same, a plurality of type-bearing plates or spindles carried by said type-

wheel and capable of reciprocating vertically, a printing character carried by the upper end of each of said plates or spindles, an alignment finger adapted to engage with and lock 5 said type-wheel, a hammer adapted to engage with one of said type-bearing plates or spindles when the wheel is locked, a finger plate pivoted to the frame of the machine, connections between said finger plate and said alignment finger and said hammer for simultaneously operating said alignment finger and said hammer, two ribbon carrying spools, one

on each side of the type-wheel, an ink ribbon extending from said spools over the periphery of the type-wheel, ratchet teeth on one of said 15 spools, and a pawl carried by said finger plate and engaging with said ratchet teeth, substantially as described.

This specification signed and witnessed this 26th day of August, 1893.
